(57) **CLAIM**

The ornamental design for an orthopedic glove, as shown and described.

DESCRIPTION

FIG. 1 is a front elevational view of the orthopedic glove showing my new design;

FIG. 2 is a rear elevational view of the orthopedic glove and a reverse view of FIG. 1;

FIG. 3 is a top plan view of the orthopedic glove based on FIG. 1;

FIG. 4 is a bottom plan view of the orthopedic glove based on FIG. 1 and a reverse view of FIG. 3;

FIG. 5 is a left elevational view of the orthopedic glove based on FIG. 1;

FIG. 6 is a right elevational view of the orthopedic glove based on FIG. 1 and the reverse view of FIG. 5;

FIG. 7 is an inside-out elevational view of the orthopedic glove based on FIG. 1; and,

FIG. 8 is a front, perspective view of the orthopedic glove with a cut-away to illustrate the curvature of the loop design based on FIG. 1.

Although shown in the context of a right hand orthopedic glove, an orthopedic glove of the present invention may also be incorporated in a left hand orthopedic glove.

The broken lines in FIG. 7 and FIG. 8 depict internal features that form no part of the claimed design.
